UNITED STATES PATENT OFFICE.

GEORGE F. ATWOOD, OF EAST ORANGE, NEW JERSEY, ASSIGNOR TO WESTERN ELECTRIC COMPANY, OF CHICAGO, ILLINOIS, A CORPORATION OF ILLINOIS.

SIGNALING APPARATUS.

No. 897,866.

Specification of Letters Patent.

Patented Sept. 8, 1908.

Application filed February 26, 1906. Serial No. 303,017.

To all whom it may concern:

Be it known that I, GEORGE F. ATWOOD, a citizen of the United States, residing at East Orange, in the county of Essex and State of New Jersey, have invented certain new and useful Improvements in Signaling Apparatus, of which the following is a specification.

My invention relates to electrical signaling apparatus, and more particularly to a telephone set adapted to be used under conditions where it is exposed in a greater degree than usual to sources of trouble.

The telephone set of my invention is designed more particularly to be used in places where an ordinary telephone set would be rendered inoperative, or its operation interfered with, by the entrance to its working parts of insects and the like, and by trouble occasioned by rain and atmospheric disturbances, and my object is to provide a set which shall combine efficiency and ease of operation with a thorough protection of its working parts from the sources of trouble mentioned above. The novel features by means of which this object is attained are described in the following specification and defined in the appended claims.

Referring to the accompanying drawings, Figure 1 is a perspective view of a telephone set embodying my invention; Fig. 2 is a front elevation of the set with the door open, a portion of the door being broken away; Fig. 3 is a side elevation in section; and Fig. 4 is a detail of one side of the set showing one of the switches.

The telephone set illustrated in the accompanying drawings is what is commonly known as a wall set, and comprises a rectangular frame 1 secured to a back board 2 preferably of somewhat larger dimensions so as to leave a projecting portion or rim upon which the binding posts 3 may be mounted and through which screws may be driven to secure the set to a suitable support, and a door 4 for the case thus constituted. The door is secured to the case preferably by hinges 5, and may be held in its closed position by means of thumb screws 6 passing through escutcheons 7 in the door and screwing into screw-threaded lugs 8 mounted upon the inside of the case. Each thumb screw is so constructed and related to its associated escutcheon that it is loosely held therein after being unscrewed from its co-operating lugs, but may be entirely removed from the

escutcheon if desired. This is accomplished by providing the thumb screw with an enlarged externally screw-threaded head 9 connected with the winged portion of the screw by a spindle of reduced diameter which passes freely through the escutcheon. The central perforation of the escutcheon is constricted at its forward end, to prevent the direct passage of the enlarged end of the thumb-screw therethrough but this constricted portion is internally screw-threaded to correspond with the external thread of the enlarged end so that, if desired, the thumb-screw may readily be withdrawn from and replaced in its escutcheon.

The edges of the case which constitute a seat for the door when closed are provided with a facing or gasket 11 of felt or other suitable material to make a moisture and insect proof joint with the door. The door is provided with an opening 12 to furnish sound communication between the interior of the case and the exterior thereof. In order to prevent the entrance of insects and the like to the interior of the case, where they might interfere with the proper operation of the telephone apparatus mounted therein, a screen 13 of fine mesh is stretched across the opening, outside of which is placed a screen or grating 14 of coarser mesh and of heavier wire to furnish mechanical protection for the first mentioned screen, the two being held securely in position by means of a metallic rim or frame 15 fastened to the door by a number of screws as shown.

Within the case are mounted the various pieces of apparatus which go to make up the telephone set. The character of this apparatus may be varied to meet the different requirements of service. In the present instance, it comprises a generator 16 of telephone ringing current mounted upon a shelf or partition 17 extending across the inside of the case somewhat below the middle thereof, as shown, a local battery 36 of two dry cells held in the lower compartment of the case by means of a clamping yoke 18 screwed to a plate mounted on the rear wall of the case, a condenser 19 secured by means of a strap to the rear wall of the case immediately above the generator in the upper compartment, an induction coil 20 mounted above the condenser, a switch 21 having an operating shaft 22 extending through an escutcheon to the outside of the case, where it is provided

with an operating handle or lever 23, a telephone switch 24 secured to the door of the case and having its switch members in position to be actuated by a telephone hook 25, 5 and a bell or ringer 26 also mounted upon the inside of the door with its gongs in proximity to the screened opening 12 in the upper portion of the door.

The generator, condenser, induction coil, 10 telephone bell and batteries are of a familiar type, and do not require any detailed description. In order to permit the operation of the generator from the outside of the case, while preventing the entrance of moisture and insects, a stuffing box 27 comprising in the present instance a washer and an annular escutcheon with a felt ring between them, as shown, is provided for the generator shaft where it passes through the wall of the case. 15 The telephone switch-hook 25 comprises a long lever arm with a hook at its end designed to support the telephone instrument, which may be a combined transmitter and receiver of a well known type, secured to a shaft 28 which passes through the cylindrical extension of escutcheon 29 into the interior of the case, where it has secured to it a short lever arm or extension 30 the end of which is arranged to engage the switch members of 20 the switch. The short lever arm or extension 30 is normally forced against the contact members of the switch by means of a helical extension spring 31 having one end secured to the short lever arm and the other to an 25 abutment fastened to the inside of the door. When the telephone instrument is placed upon the hook, the short lever arm is withdrawn from the contact members of the switch permitting them to assume their alternative position. The movement of the telephone hook may be limited by two stops carried upon the face of the escutcheon as shown. The switch 21 mounted on one of the side walls of the case, is operated by 40 means of a cam carried on a shaft 22 journaled in the cylindrical extension of an escutcheon 32 that passes through the wall, the outer end of the shaft being provided with an operating handle or lever which is arranged 45 to be moved between two pins 33 that serve as positive limit stops, and two friction stops 50 34, one associated with each pin, to hold the lever at either end of its throw.

The various pieces of apparatus of the telephone set are connected with each other and with the binding posts 3 on the outside of the case by means of appropriate wiring, not shown. The portion of this wiring that is carried external to the case on the back board is covered and protected by a panel 55 coinciding in its dimensions with the back board, and in effect forming part thereof.

When it is desired to establish telephonic communication by means of the telephone set of my invention, the distant station is

signaled by turning the crank of the generator, and upon removing the telephone instrument from the hook 25 the telephone switch operates automatically to complete the required connections. The circuit of the 70 particular arrangement shown is such that current for the operation of the transmitter is normally supplied over the line wires; but if, for any reason, this current should be interfered with or cut off, the user, by moving 75 the operating handle 23 of switch 21 from its right hand, or normal, to its left hand position, may connect the local batteries 36 in circuit and thus guard against an interruption of communication.

When the attendant at the point having the telephone set of my invention is to be signaled, this may be accomplished by sending a current over the line to ring the bell 26, the sound of which readily passes through the screened opening 12 and is responded to by the attendant. Interference with the operation of the apparatus by the entrance of insects thereto is prevented by the screen across the opening 12, the felt facing on the door seat, the stuffing box surrounding the generator shaft, and the arrangement by which the switches in the inside of the case are actuated from the outside by means of shafts.

1 claim:

1. In a telephone set, the combination with an inclosing case provided with a door having an opening therein, of a gasket interposed between said door and the case, a screen or grating secured across said opening, a telephone bell mounted on the door with its gongs in proximity to said opening, a telephone switch and switch hook also mounted upon said door, a shaft extending through the door and connecting the switch with the switch hook, a generator mounted within said case and having a shaft extending through the wall to the exterior thereof, a stuffing box surrounding said shaft, a circuit changing switch mounted on the interior of said case, a shaft extending from the switch through the wall of the case to the exterior thereof, and an actuating handle secured to the outer end of said shaft.

2. In a telephone set, the combination with an inclosing case provided with a door having an opening therein, of a gasket interposed between said door and the case, a screen or grating of fine mesh secured across said opening, a heavier screen or grating also secured across said opening outside of said first mentioned screen, a telephone bell mounted on the door with its gongs in proximity to said opening, a telephone switch and switch hook also mounted upon said door, a shaft extending through the door and connecting the switch with the switch hook, a generator mounted within said case and having a shaft extending through the wall to the exterior thereof.

- exterior thereof, a stuffing box surrounding said shaft, a circuit changing switch mounted on the interior of said case, a shaft extending from the switch through the wall of the case 5 to the exterior thereof, and an actuating handle secured to the outer end of said shaft. 3. In a telephone set having a closed apparatus box provided with a closely fitting door having an opening therein, said opening being protected by a screen or grating of fine mesh, a telephone bell mounted within the box with its gongs in proximity to said opening, a telephone switch also mounted on the inside of the door and a switch hook mounted 10 on the outside thereof on a shaft which extends through the door and is oscillated by the switch hook to operate the switch, a generator within the case having a shaft extending through the wall to the exterior thereof, 15 an operating handle secured to said shaft, a circuit changing switch mounted on the interior of the case, a shaft extending from said switch through the wall of the case to the exterior thereof, and an actuating handle secured to the outer end of said shaft. 4. In a telephone set having a closed apparatus box provided with a closely fitting door having an opening therein, said opening being protected by an inner screen of fine mesh 20 and an outer screen or grating of heavy mesh, a telephone bell mounted on the door with its gongs in proximity to said opening, a telephone switch also mounted on the inside of the door and a switch hook mounted on 25 the outside thereof on a shaft which extends through the door and is oscillated by the switch hook to operate the switch, a generator within the case having a shaft extending through the wall to the exterior thereof, an operating handle secured to said shaft, a circuit changing switch mounted on the interior of the case, a shaft extending from said switch through the wall of the case to the exterior thereof, and an actuating handle secured to the outer end of said shaft. 5. In a telephone set having a closed apparatus case provided with a closely fitting closure, said case having an opening protected by a screen of fine mesh and a screen of heavier and stouter mesh outside said first mentioned screen, a telephone bell mounted within the case with its gongs in proximity to said opening, a telephone switch within the case and a switch hook mounted on the outside thereof, a shaft whereon said switch- 30 hook is mounted extending to the inside and oscillated by the switch hook to operate the switch, a generator within the case having a shaft extending through the wall to the exterior thereof, a stuffing box surrounding said shaft and an operating handle secured to the same, a circuit changing switch mounted on the interior of said case, a shaft extending from the switch through the wall of the case to the exterior thereof, and an actuating handle secured to the outer end of said shaft. 35
